UNITED STATES PATENT OFFICE.

BENJAMIN E. GETCHELL, OF PLAINVILLE, CONNECTICUT, ASSIGNOR TO TRUMBULL ELECTRIC MANUFACTURING COMPANY, OF PLAINVILLE, CONNECTICUT, A CORPORATION OF CONNECTICUT.

ELECTRIC RELAY.

Application filed October 18, 1923. Serial No. 689,304.

To all whom it may concern:

Be it known that I, BENJAMIN E. GETCHELL, a citizen of the United States of America, residing at Plainville, Connecticut, have invented a new and useful Electric Relay, of which the following is a specification.

My invention relates to a construction which is sometimes termed an overload relay.

10 The main object is to provide a simple, inexpensive, and reliable construction. Another object is to provide a standard type device which can be made of standard parts in different ratings.

15 Another object is to provide a construction the parts of which can be readily assembled and adjusted according to a definite standard at the factory.

Another object is to so mount the parts 20 that the factory adjustment is permanent.

Another object is to provide a construction which is practically fool-proof so that it cannot be tampered with and its rating altered.

25 The invention in its preferred form is embodied in a cartridge type device in which the body is made of two parts, one of which carries both the resistance member and the automatic circuit opening device which are given a definite and permanent adjustment at the factory. The other part serves merely as a cover which is held in place by the two terminal caps.

Fig. 1 is a perspective view of one form 30 of device embodying my invention.

Fig. 2 is a longitudinal sectional view of the same.

Fig. 3 is a transverse sectional view on the plane of the line 3—3 of Fig. 2.

40 Fig. 4 is a plan view of one of the insulating body parts with attached conducting members.

Fig. 5 is an end view of the same.

Fig. 6 is a plan view of the other insulating body part.

Fig. 7 is an end view of the same.

Fig. 8 is a perspective of a fragment of one end of one of the body parts with the anchorage member.

50 The body parts 10 and 11 are preferably

made of molded insulation and held together by the end caps 12 and 13 which serves as terminals. An intermediate contact member or terminal 14 is secured to the part 10 as will be hereinafter understood. 55

The resistance or heater member 15 has its opposite ends 16 and 17 electrically connected with the end terminal caps 12 and 13 respectively. As a convenient means of securing the end caps in place and connecting 60 them to the ends of the heater strip I may provide anchorage blocks 18 and 19 adapted to fit in notches such as 20 and 21 in the body members. Each anchorage block is provided with an extension such as 22 and 65 23 adapted to project through the ends of the heater strip and be spun or riveted over the ends of the terminal members 12 and 13 to permanently unite the parts.

In the preferred form as herein shown the 70 heater strip 15 consists of a wire which is supported on one end of a strip 24 being insulated therefrom by a layer of mica 25. The support 24 is fastened in place beneath the head of a screw 25 which screws into 75 a nut 27.

The thermostatic element consists of a bimetallic strip 28 having one end secured to the body part 10 by the screw 26 and the other end engaged by the screw 29. Between the stationary end of the strip 28 and the base of the heater support 24, I provide one or more washers 30 or layers of conducting material by which the heat developed by the resistance is transmitted to 80 the thermostatic element 28. By varying the number, thickness, and material of these washers, the time lag of operation may be varied to a considerable extent. The contact screw 29 is seated in a bushing 31 which 85 is used as a rivet to hold the contact 14 in place. When this contact screw 29 has been adjusted so that the relay operates under the desired conditions, a drop of solder or brazing metal 32 is applied to the end of 90 the contact screw at the face of the bushing 31 so as to permanently connect the parts in the proper relation and to prevent changes being made in the adjustment.

It will be noted that the resistance or 100

heater element and the thermostatic element together with its contact screw are all secured to one-half of the body of the relay, the other half 11 of the body merely serving as a cover. It is thus possible to assemble the heater and thermostat and inspect and test them in full view before the cap is applied. Between the heater and thermostatic elements I provide a strip of insulating material 23, for instance of asbestos, which fits in the channel of the body and prevents the heat from the coil 15 being directly transmitted to the thermostatic strip 28.

In assembling the parts, the contact terminal 14 is riveted to the body part 10 by the bushing 31 which carries the contact screw 29. The thermostatic strip 28 is then mounted within the body part 10 and the necessary heat transmitting washers 30 and the heater strip 24 secured in place by the screw 26 and nut 27. The anchorage blocks 18 and 19 are then located in the notches in the ends of the body part 10 and the ends 16 and 17 of the heater strip are wound around the tubular extensions 22 and 23 of the anchorage members. The other body part 11 is then laid over the part 10 and the end caps 12 and 13 slipped on the ends. The extensions 22 and 23 pass through the central openings in the ends of the caps 12 and 13. The members 22 and 23 are then riveted or spun over to secure the parts permanently together. The contact screw 29 may be properly adjusted and soldered in place either before or after the cover 11 is applied.

It will be noted that the operating parts, including the adjusting means, are mounted on the same supporting member which construction prevents any change in the pre-adjusted relation of the parts by the relative shifting of the other parts and also that means are provided to prevent tampering with or changing the factory-set calibration of the relay. The construction is such that the operating parts are permanently adjusted and inaccessibly enclosed.

I claim:

1. An electric relay comprising an insulating body portion having a channelled face, a heater element secured thereto, a thermostatic element secured to the body between the heater and the body face, a contact screw secured to said body to cooperate with the thermostatic element, an insulating cover cooperating with the body to enclose said elements, and end caps to hold the body and cover together.

2. An electric relay comprising an insulating body having a channelled face, a thermostatic element and a heat conducting strip secured to said body and having heat conducting washers therebetween, a contact screw to cooperate with the thermostatic ele-

ment, a heater element comprising a wire coiled about said strip but electrically insulated therefrom and end portions one of which contacts with said strip, a cover for the body, and end caps connected to opposite ends of said heater element.

3. An electric relay comprising an insulating housing, a thermostatic element secured therein, a contact element mounted on the housing to cooperate with said thermostatic element, a heater element comprising a metal strip having an insulating cover extending over a portion thereof and a wire connected to the strip and coiled around its insulating cover, and external connections to said heater element.

4. An electric relay comprising two insulating body portions forming a housing, a heater element, a thermostatic element and a contact screw all secured to one of said body portions and covered by the other body portion, and end caps to hold the body portions together.

5. An electric relay comprising an insulating housing, a thermostatic switch element mounted therein and having a movable contact end, a metallic bushing secured in the wall of said housing and having an interiorly threaded passage with a recess in its outer end, a headless contact screw secured in said bushing with its inner end normally in electrical contact with the movable contact end of said thermostatic switch element and with its outer end within said recess and solder in said recess covering the outer end of said screw and securing said screw in its permanently adjusted position in said bushing.

6. In a relay, a housing, a thermostatic switch having a bi-metallic member, a heater support, a heat conducting member of controlled specific thermal conductivity interposed between said bi-metallic member and said support, a heater strip wound on said support and terminals therefor.

7. In a relay, a housing, a thermostatic switch having a bi-metallic member, a heater support, a plurality of heat conducting washers interposed between said bi-metallic member and said support, a heater strip wound on said support and terminals therefor.

8. A relay including an insulating support, appurtenant thermostatic heater and switch elements and adjusting means all secured on said support in predetermined relation, a cover member for said support and end caps for securing said support and said cover member in assembled relation.

9. A relay construction including an insulating body member, thermostatic heater and switch elements and adjusting means all secured to said body member, an insulating cover member for said body member

and end caps permanently secured to said body and cover members and to said heater element and securing said members together as a unit.

5 10. A relay comprising a two-part housing, a thermostatic strip, a heater strip, a member for securing one end of each strip to one part of said housing, a contact for the other end of said thermostatic strip, a resistance wire coiled about said heater strip ¹⁰ adjacent said securing member, end caps for said housing and means for connecting the ends of said resistance wire to said end caps.

BENJAMIN E. GETCHELL.
